ABEL L. WEBSTER, OF CLEVELAND, OHIO.

Letters Patent No. 105,152, dated July 5, 1870.

IMPROVEMENT IN SEAMS FOR CANS.

The Schedule referred to in these Letters Patent and making part of the same

To all whom it may concern:

Be it known that I, ABEL L. WEBSTER, of Cleveland, in the county of Cuyahoga and State of Ohio, have invented a new and useful Improvement in Seams for Cans and other Vessels, of which the following is a full, clear, and exact description, reference being had to the accompanying drawing forming part of this specification, and in which—

Figure 1 represents sectional edge views of two adjacent plates or sectional portions of a can, shaped so that, when put together, they form a seam constructed in accordance with my improvement, and

Figure 2, a similar view of like parts after the same have been put together or the seam established.

Similar letters of reference indicate corresponding parts.

The seam which is the subject of this invention is applicable both to the sides and ends of the can or vessel, and occupies a projecting relation to said surfaces, which adds to the strength and protection of the vessel.

The invention consists in a male and female fit of the edges of the plates, the one within the other, by means of a U-shaped fold formed in the edge of the one plate or connecting section, outside of or beyond the exterior surface of said plate, and fit of the edge of the other plate or connecting section, by shouldering it within said fold, and afterward soldering the

seam along the mouth of the fold, the whole forming a cheap, simple, close, and strong seam.

Referring to the accompanying drawing—

A represents the one plate or connecting section of a can, and

B, the other plate or section thereof.

The one plate, A, has its edge bent outward, and afterward turned to form a V-shaped fold, b, within which the edge c of the adjacent plate B fits, as represented in fig. 2, after which the plates are pressed together at the joint thus formed, and the seam closed by soldering along the mouth of the fold at d. This forms a very cheap and secure seam, and the same is considerably strengthened by bending the edge c of the plate B to form a shoulder, e, which, lapping over the root of the fold b, bears against the inside surface of the plate A, and stiffens the can or vessel.

What is here claimed, and desired to be secured by Letters Patent, is—

The jog or shoulder e along the edge c of the one plate B, in combination with the fold b along the edge of the adjacent plate A, within which the edge c of the plate B fits, essentially as shown and described.

ABEL L. WEBSTER.
